UNITED STATES PATENT OFFICE.

AKOS J. HALL, OF CLEVELAND, OHIO.

STAIR STRUCTURE.

1,385,209.

Specification of Letters Patent. Patented July 19, 1921.

Application filed September 23, 1919. Serial No. 325,613.

To all whom it may concern:

Be it known that I, AKOS J. HALL, a citizen of the United States, residing at the city of Cleveland, county of Cuyahoga, State of Ohio, have invented new and useful Improvements in Stair Structures, of which the following is a specification.

This invention relates to an improvement in stair structure, and particularly to that 10 class in which the elements are constructed of sheet metal.

The invention consists of metallic stringers and stair units, each comprising an integral tread and riser; the risers and treads 15 being provided with lugs adapted to pass through slots formed in the stringers, and after the lugs have been inserted in the slots they are bent at right angles against the sides of the stringers for securely fastening 20 the stair units in place.

The invention consists of certain novel features of construction and combination of parts which will be hereinafter described and pointed out in the claims.

25 In the accompanying drawing:

Figure 1 is a perspective view of a portion of a stairway showing the elements assembled;

Fig. 2 is an enlarged detail view showing 30 the post in section and a stringer in elevation to illustrate the manner of fastening the stringer and post together and the stair units to the stringer and post;

Fig. 3 is a detail transverse sectional view 35 of the stringer and a stair unit; and Fig. 4 is a detail view.

In the drawing, 1 and 2 represent the stringers, which are constructed of sheet metal, having their longitudinal edges bent 40 outwardly at right angles as at 3, 3. The upper and lower portions may be formed in any ornamental fashion as indicated at 4, 4 for the purpose of strengthening and giving 45 rigidity to the stringer. Each stringer is provided with alternate horizontal and vertical slots 5 and 6 throughout its length.

The stair units each consist of a tread 7 and a riser 8. The outer edge of the tread is bent upwardly as at 9, and then rounded 50 at 10, and then bent inwardly, forming a socket for the insertion of the upper edge of the riser 8 of the adjacent stair unit, thereby producing a finished edge between the tread of one unit and the riser of another unit. 55 The riser will in this manner also afford a

support for the longitudinal outer edge of the tread. In providing the upwardly extending flange or portion 9 on the tread a recessed portion is produced in the tread for the reception of a filler, of felt, rubber sheet- 60 ing or cement not shown.

The ends of the tread and riser of each unit are provided with lugs 11 and 12, adapted to be inserted or passed through the slots 5 and 6, respectively, of the stringers 1 65 and 2. It is preferred, but not entirely essential, that the lugs be bent in alternate directions against the outer walls of the stringers.

The lugs are made or formed of a size to 70 afford a sufficient support and fastening for the tread and riser, and render a stronger structure than by employing bolts. Furthermore the structure produced is simpler in construction and consists of a fewer parts, 75 and can be manufactured and assembled at a smaller cost, than would be possible if bolts and nuts were employed.

At the foot of the stair case, as shown in this instance, a hollow sheet metal post 13 80 is provided. The post has slots 14, 14 therein with which slots 15, 15 formed in an angle plate 16, fastened to the lower end of the stringer 2, register. Bolts 17, 17 are adapted to be inserted through the slots of the plate 85 16 and post 13 for fastening them together. Each bolt 17 is provided with a tapered opening for the reception of a similarly shaped wedge 18 for securing the bolt in place.

A riser 19 is provided at the foot of the 90 staircase, and one end of the riser is connected to the stringer 1 by lugs 11, in the same manner as the riser of a stair unit, and the opposite end has its lugs 11 passing through slots 20 formed in the post 13. 95

A metal molding strip 21 of any configuration is applied to the exposed stringer 2, and has its edges bent at right angles as at 22, 23 to overlap and engage the edges 3, 3 of the stringer 2. The lower angular edge portion 100 23 is provided with an upstanding flange 24 to engage the inner wall of the stringer 2 for insuring a more rigid connection of the molding to the stringer.

What I desire to secure by Letters Patent, 105 and claim as my invention, is:-

1. In a stair structure, the combination of a plurality of stair units consisting of a tread and riser, lugs formed at the lateral edges of the tread and riser of each unit, 110

2
and stringers provided with slots, said lugs extending through the slots and bent against the walls of the stringers for fastening the units and stringers together.

- 5 2. In a stair structure, the combination of a plurality of stair units consisting of a tread and riser, each tread being bent at the outer longitudinal edge to form a socket in which the upper edge of the riser of an adjacent unit may be received for holding said edges of the tread and adjacent riser together and forming a support for the edge of the tread, lugs formed at the lateral edges of the tread and riser, and stringers provided 10 with horizontal and vertical slots through which the lugs of the units extend, said lugs being bent against the walls of the stringers

for fastening the units and stringers rigidly together.

3. In a stair structure, the combination of 20 a plurality of stair units, each composed of a tread and riser and stringers, one of said stringers having the edges thereof bent outwardly, lugs on the lateral edges of the treads and risers, said stringers provided 25 with slots for the reception of the lugs, said lugs bent against the walls of the stringers for fastening the stair units thereto, and a molding strip having inwardly extending portions adapted to engage the outwardly extending edges of one of the stringers for enclosing the lugs. 30

AKOS J. HALL.
